UNITED STATES PATENT OFFICE

ARTHUR F. POOLE, OF ITHACA, NEW YORK, ASSIGNOR TO POOLE MANUFACTURING CO.
INC., A CORPORATION OF NEW YORK

ELECTRIC CLOCK AND THE LIKE

Application filed January 31, 1927. Serial No. 164,674.

This invention relates to electric clocks or the like, and is in the nature of an improvement upon the type of clock illustrated in my prior U. S. patent Number 1,531,026, issued March 24, 1925.

An object of the invention is to provide an improved and simplified clock mechanism which will operate without attention for a long period of time; which will consume a minimum amount of current; with which there will be no arcing of contacts when circuits are made and broken; and which will be relatively simple, durable, compact, dependable and inexpensive.

15 A further object of the invention is to provide an improved polarized electromagnet; with which both limits of oscillation of the armature may be varied uniformly and simultaneously in a simple, novel and accurate manner.

20 Various other objects and advantages will be apparent from the following description of an embodiment of the invention, and the novel features will be particularly pointed out hereinafter in connection with the appended claims.

In the accompanying drawings:—

Fig. 1 is an elevation of a clock constructed in accordance with this invention;

30 Fig. 2 is a plan of the same;

Fig. 3 is a sectional elevation of a part of the same, the section being taken approximately along the line 3—3 of Fig. 2;

35 Fig. 4 is a sectional elevation through a part of the polarized electromagnet, with the section taken approximately along the line 4—4 of Fig. 2;

Fig. 5 is a side elevation of the clock;

40 Fig. 6 is a sectional elevation through a part of the contact mechanism;

Fig. 7 is a diagram of the circuits of the clock in the preferred form;

45 Fig. 8 is a sectional elevation of the clock, with the section taken approximately along the line 8—8 of Fig. 2;

Fig. 9 is an elevation of the polarized electromagnet;

50 Fig. 10 is a sectional elevation through the balance wheel shaft and illustrating the mov-

able anchorage for one end of the hair spring in one of its positions;

Fig. 11 is a similar elevation but with the anchorage in another of its positions; and

Fig. 12 is a diagram of a modified circuit 55 arrangement adapted for storage battery operation, which may be used instead of that shown in Fig. 7.

In the illustrated embodiment of the invention, the time train mechanism 1, Fig. 1, is mounted in any usual or suitable manner in a clock frame 2 formed of spaced plates, as usual in horological mechanism. The time train is driven through a ratchet wheel 3 carrying a driving pinion 4.

60 A balance wheel 5 is mounted upon a balance wheel shaft 6, which extends between and is mounted for oscillation in suitable bearing screws 7 and 8 (Figs. 2 and 5) as usual in clock mechanisms. The balance wheel carries the usual or any suitable roller pin 9 which cooperates with and oscillates the forked end of a lever 10 somewhat resembling in action the usual pallet lever.

The lever 10 is secured upon a shaft 11 which extends between and is rotatably mounted in spaced plates of the frame 2, as shown clearly in Fig. 2. The shaft 11 extends forwardly through one of the plates of the frame 2, and carries an arm 12 (Figs. 1 and 5).

65 The arm 12, at a distance from its pivot, pivotally mounts a driving pawl 13, and a spring 14 connects the pawl 13 and a suitable part of the arm 12, so as to urge the nose of the pawl 13 yieldingly and resiliently into contact with the teeth of the ratchet wheel 3. Thus when

70 when the balance wheel oscillates, it will oscillate the lever 10 and the arm 12, and the pawl 13 of the latter will drive the time train through the ratchet wheel 3.

75 Regular oscillations of the balance wheel and its shaft may be obtained by a hair-spring 15, one end of which is connected to the balance wheel shaft, and the other end of which is adjustably anchored by a wedge pin 16 to an arm 17 extending from an armature 18 of a polarized electromagnetic device 19.

80 The movements of the armature are therefore imparted to the spring 15 to vary the tension of the same and this variation in tension of the 100

hair spring 15 is utilized to maintain the balance wheel and its shaft in oscillation.

While the usual regulating mechanism commonly found in clocks for regulating the oscillations of the balance wheel through the hair spring, may be applied to the hair spring 15, I have found it advantageous to provide a second or regulating hair spring 20 connected at one end to the balance wheel shaft 10 and at its other end by a wedge pin 21 to a bracket pin 22 extending from the clock frame. A regulating arm 23 having regulating pins 24 straddling the outer convolution of the hair spring 20 may be pivotally mounted upon the adjustable bearing screw 8 and confined thereon between the head of the screw and a frictional spider 25 which frictionally holds the arm 23 in angularly adjusted positions. One end of the arm 23 may have an angular ear 26 extending forwardly through an arcuate slot 27 in one of the plates of the frame 2 for manipulation in regulating the period of oscillation of said balance wheel, as usual in clock mechanisms of the balance wheel type.

The rearward plate of the clock frame 2 may have a tongue 28 (Figs. 2, 5 and 9) struck outwardly therefrom, which tongue is connected at its free end to a bar 29 connecting the two projecting core ends 30 of two electromagnets 31 of the electromagnetic device 19. The two electromagnets 31, at their opposite ends, are secured to a bar 32 which is secured to rearwardly extending ears 33 of the clock frame, so that the two electromagnets will be mounted upon the clock frame. A U-shaped permanent magnet 34 extends along one side of the pair of electromagnets 31, with its arms extending into and terminating in proximity to and between the ends of the cores of the two electromagnets. The upper arm of the permanent magnet terminates above the armature 18 but in proximity thereto. The lower end is secured by a screw 35 to the bar 32 which bar may be of good magnetic flux conducting material, so that the permanent magnet acts as a flux conducting part between the ends of the pair of electromagnets and including in the flux path the armature 18.

The armature 18 is pivotally mounted intermediate of its ends by a pointed bearing pin 36 riveted at its blunt end to an upstanding ear 37 of a plate 38, and by a pointed bearing screw 39, which is adjustable through another and opposite ear 40 of the plate 38. The plate 38 is of resilient flexible non-magnetic material, such as spring brass, and is normally arcuate in shape between its ends and disposed between the armature and the adjacent ends of the electromagnet cores 30. The plate 38 may be forked at its ends, so as to straddle the core ends 30 and extend between them, and be disposed with the concave face of the plate toward the connecting bar 29.

The plate 38 is clamped against the bar 29 by a screw 41 which passes through a clearance aperture 42 in the upper arm of the permanent magnet 34 and through a clearance aperture 43 in the armature (see Figs. 4 and 5). This screw has a reduced threaded end passing through an aperture 44 in the plate 38 and threaded into the bar 29, as shown in Fig. 4. The shoulder at the inner end of the threaded portion of this screw bears against the upper face of the plate 38, so that the screw 41 clamps the plate 38 against the bar 29 and confines the plate in straddled relation over the core ends 30. By adjusting the screw 41, the plate 38 may be sprung intermediate of its ends toward or from the bar 29 to various extents, and thereby the pivots 36 and 39 of the armature may be shifted toward or from the electromagnets. This movement of the pivots of the armature carries the armature bodily toward and from the core ends 30 of the electromagnets, so as to equally limit the throw of the armature in both directions as it rocks due to varying magnetic conditions in the electromagnets 31. The armature, which is of magnetic material, may have a thin plate 18^a of non-magnetic material (Fig. 9) secured to its face abutting the core ends 30 so as to prevent the armature from sticking to the core when striking the same.

The two electromagnets may be connected in series with one another and be so wound that when a current passes through them, the core ends 30 will always have opposite polarities. Since the magnet 34 serving to complete the flux path between the ends of the electromagnets is a permanent magnet, the upper end above the armature will always have a polarity similar to one of the core ends and also opposite to that of the other core end, even though the polarities of the core ends 30 may fluctuate with changes in the direction of current through the electromagnets. Since the armature 18 is disposed in proximity to the upper end of the permanent magnet, it will also be magnetized and have the same polarity as that end of the permanent magnet. Hence, one end of the armature will always be attracted and the other end repelled by the core ends, in one direction or the other depending upon the direction of current through the electromagnets.

A pair of leaf spring contact fingers or elements 45 and 46 (Figs. 2, 5 and 3) are secured to an insulating block or support A, so as to extend on opposite sides of the lever shaft 11, in position for contact with contact tips or terminals 47 and 48 of a contact member or arm 49 which is fired upon and oscillates with the shaft 11. The contact arm or member 49 includes arms extending in opposite directions from the shaft and bent angularly thereto in opposite directions at their free ends, so that the contact tips or terminals 130

47 and 48 will be spaced apart, considered lengthwise of the axis of the shaft 11, and the leaf springs 45 and 46 are also spaced apart from one another along the shaft 11 in a similar manner. As the shaft 11 oscillates with the balance wheel, the contact tips or terminals 47 and 48 will contact alternately with the leaf contact springs 45 and 46.

An abutment strip 50 may be disposed adjacent to each strip 45 and 46 in spaced relation to the free ends of the same, and also secured to the block or support A. A screw 51 is threaded through the free end of each strip 50, so as to abut endwise against its corresponding contact spring 45 or 46 and limit movement of the latter toward the shaft 11. By adjusting the screws 51, the extent to which the contact springs 45 and 46 may flex of their own accord or bias toward the shaft 11 may be selectively varied, and thus the instants at which contact is made between the arm 49 and the springs 45 and 46 may be varied to some extent. Since the springs 45 and 46 and their abutment strips 50 are spaced apart from one another, considered lengthwise or endwise of the shaft 11, neither spring 45 or 46 and its abutment strip will interfere with free access to the head of the screw forming the adjustable abutment for the other spring. A short leaf spring 52 may be secured to each abutment strip 50 with its free end spaced from the strip 50 where the screw is threaded therethrough, and may be provided at its free end with an aperture through which the screw 51 may pass. Thus the springs 52 by yieldingly bearing against the heads of the screws will frictionally hold the screws against turning, and thus against changes in adjustment which are not intended or manually given.

Referring now to Fig. 7, a diagram of the preferred circuit arrangement is illustrated. The electromagnets 31 which are connected in series are connected at one end by a wire 53 to a suitable source of electric energy 54, such as a battery. The electromagnets 31 are also connected at their other end by wire 55 to one side of a suitable condenser 56, the other side of the condenser being connected by a wire 57 to the frame of the clock, and thus to the lever shaft 11 and the arm 49. One of the spring contacts, such as 46, is connected by a wire 58 to the other side of the battery 54, and the other of the contacts 45 may be connected by wire 59 to wire 53.

From this description of the circuits, it will be observed that when the arm 49 contacts with the spring contact element 46, a circuit will be established from the battery 54 through the clock frame to the condenser, and through the condenser and the electromagnets 31 back to the battery. At the closing of such a circuit, there will be a surge of current through the condenser and electromagnets, and this surge of current will set up

a magnetic field in the electromagnets acting upon the armature 18, and cause a movement of the armature in one direction. This movement, through the arm 17 of the armature causes a tightening or loosening of the hair spring 15. This current will be only for an instant, that is, momentary, while the condenser 56 is charging, the condenser preventing the passage of direct current except for the momentary surge when the circuit is closed. This surge however is sufficient to operate the armature 18.

During further oscillation of the balance wheel, when the arm 49 makes contact with the other leaf spring or contact element 45, at which time of course the arm 49 will be out of contact with the spring 46, a new circuit will be established, shunting the condenser 56 directly across the electromagnets 31. This circuit will include the condenser 56, wire 57, the clock frame 2, arm 49, contact spring 45, wire 59, wire 53, the electromagnets and wire 55 back to the condenser. The condenser, which was charged by the previous surge of current, will now be discharged through the electromagnets and will send a surge of current in the opposite direction therethrough which will cause a reversal of polarity of the core ends 30, and consequently a rocking of the armature 18 in the opposite direction to cause a different tension in the hair-spring 15.

The condition of the hair spring 15 when the armature is at one limit of its movement is shown in Fig. 10, and another condition of the hair spring when the armature is in the other position is shown in Fig. 11. The armature during its movements therefore tends to wind the hair spring in one direction or the other depending upon its direction of oscillation at any time. This movement, however, which is caused by the alternate closure of the two circuits described, must be such that the hair spring will be wound or moved in a direction opposite to that in which the balance wheel is traveling at the time the movement is made, in order that the balance wheel will be maintained in oscillation by these variations in the tension of the hair spring.

In order that there may be no danger of a poor circuit connection between the shaft 11 carrying the contact arm 49 and the clock frame 2, I may provide a coil of non-resilient wire 60 loosely around the shaft 11, firmly attach one end of the coil to the shaft, and firmly secure the other end of the coil to the clock frame, as shown clearly in Fig. 2. This loose coil 60 will thus furnish a good electrical circuit between the shaft 11 and the clock frame, without exerting any material influence upon the oscillations of the shaft 11 and independently of any lubricating oil on the bearings of the shaft 11. It will also be understood that the arm 49 should break contact

with one spring 45 or 46 before it makes contact with the other.

In the operation of a clock constructed in this manner, let it be assumed that the balance

5 wheel 5 and its shaft 6 are oscillating in a clockwise direction (Fig. 8). During such oscillation, the lever 10 will be rocked in a counterclockwise direction, (also in Fig. 8) and the contact 49 will carry its contact tip 10 48 into engagement or contact with the leaf spring or contact element 46 before the balance wheel reaches the limit of its oscillation in a clockwise direction (Fig. 8). When the arm 49 does contact with spring 46, a circuit 15 will be established from the battery through the series-connected condenser 56 and the electromagnets 31, which will cause a momentary surge of current through the electromagnets in a direction to shift the arm 17 from the 20 position shown in Fig. 11 to the position shown in Fig. 10, which will be in effect a movement in a direction to wind the spring 15 in a direction opposite to that in which the balance wheel at that moment is traveling. 25 The balance wheel will continue its movement in the same direction in the usual manner and when returning, it will open the battery circuit previously established and shortly after passing the position of the parts 30 shown in Fig. 8, the arm 49 will contact with the spring 45 and shunt the condenser across the electromagnets 31. Since the condenser was charged by the previous surge of current from the battery, it will now discharge 35 through the electromagnets and cause a momentary surge of current in the opposite direction through the electromagnets, and cause a rocking of the armature in a reverse direction to carry the arm 17, to which the hair 40 spring 15 is connected, from the position shown in Fig. 10 to the position shown in Fig. 11, which will be in a direction opposite from that in which the balance wheel is moving at that particular instant. These changes in the 45 tension of the hair spring thus produced will give the necessary impulses or bias to the balance wheel to maintain it in oscillation, and the balance wheel will in turn drive the time train so long as its oscillations are maintained.

It will be noted that the current from the battery is utilized only during alternate oscillations or movements of the armature, and that even when the battery circuit is closed, 50 there will only be a momentary surge of current regardless of how long the circuit remains closed. Thus the current consumption required for the operation of such a clock or the like will be a minimum. However, in view 55 of the fact that only a momentary surge of current is utilized, the voltage of the source of energy or battery 54 should preferably be quite considerable, such as twenty volts or more in order that the electromagnets will 60 have energy sufficient to rock the armature.

The natural period of oscillation of the balance wheel may be varied by adjustment of the regulator arm 23, as usual in clock mechanisms.

In some instances it may be desirable to 70 operate such a clock mechanism from a battery having a relatively low voltage, such as the ordinary storage battery used in automobiles and having a voltage of only six volts. The circuit for such a battery is illustrated 75 diagrammatically in Fig. 12. The mechanism of the clock is the same as explained hereinbefore, except that two condensers 56^a and 56^b are utilized in place of a single condenser 56. Referring particularly to Fig. 80 12, a battery or source of current 61 is connected at one end to the wire 62 which connects the electromagnets 31 in series. The other end or terminal of the battery is connected by a wire 63 to the contact arm 49 and 85 also by branch wires 64 and 65 to one side of each of the condensers 56^a and 56^b. The other side of one electromagnet is connected by a wire 66 to one of the contact springs 45, and the other terminal of the other of 90 the electromagnets 31 is connected by a wire 67 to the other of the contact springs, such as 46. The wire 67 is also connected to the other side of the condenser 56^b, and the wire 66 is also connected to the other side of the condenser 56^a.

The operation of this modified circuit arrangement would be as follows: When during the oscillation of the balance wheel the contact arm 49 engages with the contact 100 spring 45, a circuit will be established from the battery 61 through wire 63, contact arm 49, contact spring 45, wire 66 and one of the electromagnets 31, back to the battery through wire 62. This causes a rocking of 105 the armature 18 in one direction, there being no current flow at that time in the other of the electromagnets. This rocking of the armature 18 causes a change in the tension of the hair spring 15 as before, and when the 110 balance wheel travels in the opposite direction, the contact arm 49 will be shifted in a manner to open this circuit previously established and be moved into engagement with the contact spring 46. At the opening 115 of the previously closed circuit, the condenser 56^a, which is connected in shunt across the arm 49 and contact 45, will prevent any sparking between the spring 45 and the arm 49 as they separate.

At the closing of the new circuit with the spring 46, the current will flow from the battery 61 through wire 63, contact arm 49, contact spring 46, wire 67, the other of the electromagnets 31, and wire 62 back to the battery. This causes a rocking of the armature 18 in the other direction, and thereby a change in the tension of the hair spring 15. The condenser 56^b being in shunt across arm 49 and spring 46 prevents arcing therebe- 120 125 130

tween when the circuit is opened by their separation. These changes in the tension of the hair spring 15 maintain the balance wheel in oscillation as before. While the 5 current consumption in such a modified circuit arrangement is considerably higher than for the circuit described in Fig. 7, such a modified battery circuit is usually used in connection with a storage battery, where the 10 relative amount of current utilized is not important or objectionable.

It will be obvious that various changes in the details, which have been herein described and illustrated in order to explain the nature 15 of the invention, may be made by those skilled in the art within the principle and scope of the invention as expressed in the appended claims.

I claim:

20 1. In an electric clock or the like, an oscillating control element, a spring connected to said element for securing regular oscillations thereof, polarized electromagnetic means for varying the influence of the spring upon said element, a source of electrical energy, a condenser, and circuit means including said electromagnetic means, said source of energy, and said condenser, and rendered effective automatically through the oscillations of 25 said element for causing surges of current through said electromagnetic means in opposite directions, alternately, in a manner to vary the influence of said spring upon said element and thereby maintain said element 30 in oscillation.

2. In an electric clock or the like, an oscillating control element, a spring connected to said element for securing regular oscillations thereof, polarized electromagnetic means 40 operable upon said spring to vary the force of the latter upon said element, a source of electrical energy, a condenser, and circuit means including said electromagnetic means, said source of energy and said condenser and rendered effective automatically through the oscillations of said element for causing surges of current through said electromagnetic means in opposite directions, alternately, in a manner to vary the action of said 45 spring upon said element and thereby maintain said element in oscillation.

3. In an electric clock or the like, an oscillating control element, a spring connected to said element for securing regular oscillations 55 thereof, polarized electromagnetic means for varying the influence of the spring upon said element, a source of electric energy, a condenser in series with said electromagnetic means, contact means operable through the oscillations of said element, and circuits connecting said source of energy, said contact means and said condenser and electromagnetic means in such a manner that surges of 60 current from said source of energy will be sent through said electromagnetic means

alternately and in opposite directions by the operation of said contact means, whereby said element will be maintained in oscillation by the varying influence of said spring thereon.

4. In an electrical clock or the like, an oscillating control element, a spring connected to said element for securing regular oscillations thereof, polarized electromagnetic means for varying the influence of said spring upon 70 said element, a condenser connected in series with said electromagnetic means, a source of energy, contact elements, a contact member oscillatable through the oscillations of said element and making and breaking contact 75 with said contact elements alternately, a circuit including said contact member, said series connected condenser and electromagnetic means, and one of said contact elements, a second circuit including said source of 80 energy, the other of said contact elements, said contact member and said series connected condenser and electromagnetic means, whereby when said circuit is completed by contact of said contact member and said other 85 of said contact elements, a surge of current will pass from said source of energy through said condenser and electromagnetic means in one direction and cause a change in the influence of the spring upon said element by 90 said electromagnetic means, and when the first circuit is completed by contact of said one of the contact elements and said contact member, said condenser will be shunted across said electromagnetic means and will 95 discharge a surge of current through said electromagnetic means in the opposite directions to again vary the influence of the spring upon said element by a reverse operation of 100 said electromagnetic means.

5. In an electric clock or the like, an oscillating control element, a spring connected to said element for securing regular oscillations thereof, polarized electromagnetic means for varying the influence of the spring upon said element, a source of energy, a condenser, and means including circuits controlled by the oscillations of said elements for conducting a surge of current from said source through 105 said electromagnetic means in one direction to vary the influence of the spring upon said element and charge said condenser at one instant in the oscillations of said element, and for causing a discharge of the condenser through said electromagnetic means in the reverse direction to cause a restoration of the influence of said spring upon the element to initial condition at another instant in the oscillations of said element, whereby said element will be maintained in oscillation by the 110 variations in the influence of the spring thereon produced by the operation of said electromagnetic means.

6. In an electric clock or the like, an oscillating control element, a spring connected to 115

said element for securing regular oscillations thereof, polarized electromagnetic means for varying the influence of the spring upon said element, a source of electric energy, a condenser, means including a circuit connecting 5 said source of energy, said electromagnetic means and said condenser rendered effective at one instant in the oscillation of said element for causing an operation of said electromagnetic means to vary the influence of the 10 spring upon said element and for charging said condenser, and means operable automatically at another instant in the oscillations of said element for shunting said condenser across the electromagnetic means to cause a surge of current through said electromagnetic means in a reverse direction and another operation of said electromagnetic means to restore the original influence of the 15 spring upon said element, whereby said element will be maintained in oscillation by the variations in the influence of the spring thereon.

7. In an electric clock or the like, an oscillating balance wheel, a hair spring connected at one end to said balance wheel for causing regular oscillations thereof, electromagnetic means having a movable armature connected to said hair spring for changing its influence 20 upon said balance wheel, a contact member oscillatable concomitantly with said balance wheel, contact elements with which said member cooperates alternately at different instants in the oscillations of said balance 25 wheel, a source of electric energy, and circuits including said contact member, said contact elements and said electromagnetic means for causing movements of said armature synchronously with the oscillations of 30 said balance wheel, whereby said balance wheel will be maintained in oscillation by the varying influence of said armature upon said hair spring.

8. In an electric clock or the like, an oscillating balance wheel, a hair spring connected to said balance wheel to secure regular oscillations thereof, polarized electromagnetic means having an armature oscillating with changes in direction of current passing 35 through said electromagnetic means, said armature being connected to said spring for varying the tension of said hair spring at each oscillation of said armature, a condenser connected in series with said electromagnetic means, a source of electric energy, and means including circuits connected to said source of energy, said condenser and said electromagnetic means, and in turn controlled by the 40 oscillations of said balance wheel for sending a surge of current through said electromagnetic means and condenser at one instant in the oscillation of said balance wheel to cause a change in the tension of said spring, and for shunting said condenser across said 45 electromagnetic means at another instant in

the oscillation of said balance wheel to send a surge of current through said electromagnetic means in the opposite direction and thereby cause a restoration of the tension of said spring to initial condition.

9. In an electric clock or the like, an oscillating balance wheel, a hair spring connected to said balance wheel for securing regular oscillations thereof, polarized electromagnetic means having an armature oscillating 50 in accordance with reversals of current through said electromagnetic means, said armature being connected to said hair spring for varying the tension thereof by the oscillation of said armature, a contact member connected to and oscillatable by said balance wheel, a pair of contact elements with which said member contacts alternately at different instants in the oscillation of said balance wheel, a source of electric energy, a condenser, a primary circuit including said source of energy, said electromagnetic means, said condenser, said contact member, and one of said contact elements, whereby a closing of said circuit by said member and one of said contact elements will cause a surge of current through said electromagnetic element in one direction to cause a movement of said armature and through it a change in the tension of said hair spring, and a shunting circuit including said electromagnetic means, said condenser, said contact member and the other of said contact elements for shunting said condenser across said electromagnetic means at a different instant in the oscillation of said 55 elements, when said primary circuit is open, to cause a surge of current through said electromagnetic means by the discharge of said condenser, and thereby cause another movement of said armature in a manner to cause a return of the hair spring to its initial tension, whereby said balance wheel will be maintained in oscillation by the variations in tension of said hair spring.

10. In an electric clock or the like, an oscillating balance wheel, a hair spring connected to said balance wheel for securing regular oscillations thereof, polarized electromagnetic means having an armature oscillating in accordance with reversals of current through said electromagnetic means, said armature being connected to said hair spring for varying the tension thereof by the oscillation of said armature, a contact member connected to and oscillatable by said balance wheel, a pair of contact elements with which said member contacts alternately at different instants in the oscillation of said balance wheel, a source of electric energy, a condenser, a primary circuit including said source of energy, said electromagnetic means, said condenser, said contact member, and one of said contact elements, whereby a closing of said circuit by said member and one of said contact elements will cause a surge of current 100

through said electromagnetic element in one direction to cause a movement of said armature and through it a change in the tension of said hair spring, a shunting circuit including said electromagnetic means, said condenser, said contact member and the other of said contact elements for shunting said condenser across said electromagnetic means at a different instant in the oscillation of said elements, when said primary circuit is open, to cause a surge of current through said electromagnetic means by the discharge of said condenser, and thereby cause another movement of said armature in a manner to cause 10 a return of the hair spring to its initial tension, whereby said balance wheel will be maintained in oscillation by the variations in tension of said hair spring, and means for varying the natural period of oscillation of 15 said balance wheel.

11. In an electric clock or the like, an oscillating balance wheel, a hair spring connected to said balance wheel for securing regular oscillations thereof, a lever oscillated 20 by said balance wheel, a pair of contact arms on said lever and having contact ends spaced apart at different points along the length of the axis of oscillation of said lever, a pair of contact springs extending into position for 25 contact by said contact portions alternately during the oscillations of said lever, adjustable abutments for limiting the movements of said contact springs toward the paths of said contact ends, and means including circuits 30 controlled by said contact spring and said arms for varying the influence of said spring upon said wheel to thereby maintain said balance wheel in oscillation.

12. In an electric clock or the like, an oscillating balance element, a hair spring connected at one end to said balance element, electromagnetic means having an armature movable between two positions and connected to the free end of said spring to tension the 40 same varying amounts upon the oscillation of said armature, a contact device having a controlling member operated directly by said balance element in synchronism therewith, and means including said contact device and 45 said electromagnetic means for rocking said armature in synchronism with said element to vary the stress of said spring at each oscillation of the element and thereby maintain said element in oscillation.

13. In an electric clock or the like, an oscillating balance wheel, a hair spring connected to the balance wheel for securing regular oscillations thereof, electromagnetic 50 means for varying the tension of said spring, and means controlled by said balance wheel and including said electromagnetic means and a pair of circuit rendered effective by the balance wheel alternately for varying 55 the tension of said spring in synchronism

with the oscillations of said wheel to thereby maintain said wheel in oscillation.

14. In an electric clock or the like, a balance wheel, a spring for imparting oscillatory movements to said wheel, a member connected to and oscillated by said balance wheel in synchronism therewith, pawl means carried by said member, a time train including a ratchet wheel driven by said pawl means, and means including an electric circuit made and broken in synchronism with the oscillations of said balance wheel to vary the torque of said spring on said wheel and thereby maintain said balance wheel in oscillation.

15. In an electric clock or the like, a balance wheel, a member connected to and oscillated by said balance wheel in synchronism therewith, pawl means carried by said member, a time train including a ratchet wheel driven by said pawl means, a hair spring 80 connected to said balance wheel for securing regular oscillations thereof, and means including circuits made and broken in synchronism with the oscillations of said balance wheel for varying the tension of said spring 85 to maintain said balance wheel in oscillation.

16. In an electric clock, an electromagnetic device including a pair of electromagnets having parallel spaced apart cores, a concave plate of non-magnetic resilient material extending between said cores and bearing against the ends of the electromagnets with the concave face toward the electromagnets, an armature rockably mounted intermediate of its ends on said plate at a point between said cores, means for clamping said plate against said electromagnets and adjustable to compress said plate toward the electromagnets variable amounts at a point intermediate the ends of said plate, whereby 100 said armature will be carried toward or from said cores by the flattening of said plate and the limits of oscillation of the armature varied equally, and a flux conducting bar having an end adjacent said armature and its opposite end adjacent the opposite end of said electromagnets.

17. In an electric clock, an oscillatory time member, a spring connected to and synchronizing the oscillations of said member, an electromagnet, an oscillating pivoted armature for said electromagnet connected to said spring for varying the stress therein as the armature oscillates to maintain said member in oscillation, and means for varying equally 115 the limits of movement of said armature on both sides of its pivot.

ARTHUR F. POOLE.
